UNITED STATES PATENT OFFICE.

JAMES A. KENNY, OF CHICAGO, ILLINOIS.

ELECTRICAL PROTECTIVE APPARATUS.

No. 882,892.

Specification of Letters Patent. Patented March 24, 1908.

Application filed January 7, 1904. Serial No. 188,056.

To all whom it may concern:

Be it known that I, JAMES A. KENNY, a citizen of the United States, and a resident of Chicago, Cook county, Illinois, have invented certain new and useful Improvements in Electrical Protective Apparatus, of which the following is a full, clear, and exact description.

This invention, while susceptible of use so far as certain of its features are concerned in other situations, has for its object more particularly to provide improved means for guarding telephone, telegraph or like instruments and the users thereof, against injury from lightning and high tension currents that may invade the circuit in which such instruments are employed.

The invention consists in the features of improvement hereinabove described, illustrated in the accompanying drawings and particularly pointed out in the claims at the end of this specification.

Figure 1 is a plan view (parts being shown in section) of an apparatus embodying my invention. Fig. 2 is a view inside elevation. Fig. 3 is a view in vertical cross section on line 3--3, of Fig. 1. Fig. 4 is a similar view on line 4--4, of Fig. 1. Fig. 5 is a similar view on line 5--5, of Fig. 1. Fig. 6 is a detail plan view of one of the carbons.

A designates the base of the apparatus, this base being formed of any suitable insulating material, such as hard rubber, vulcanized fiber, porcelain or the like.

In the accompanying drawings my invention is shown as more particularly adapted for use in an all-metallic telephone circuit and the mechanism employed to prevent injury from lightning or from high potential currents that may trespass upon the line circuit, is shown as duplicated for the two sides of the line circuit, but it will be understood that when the invention is employed in a grounded circuit such duplication will not be necessary.

Upon the insulating base A, in the form of the invention shown, there is mounted at each side of the vertical longitudinal center of the base, a pair of carbon-holders that serve to maintain the carbons at proper distances apart. One of these carbon-holders, in the form of the invention shown, comprises a socket or cup 2 wherein the carbon B is set. The socket 2 is preferably formed with an annular internally projecting rib 3 adapted to enter a corresponding groove in

the periphery of the carbon B. The purpose of the rib is to more securely retain the carbon B within the socket and the walls of the cup 2 will have sufficient elasticity to permit the carbon B to be forced downward until the rib 3 enters the groove in the periphery of the carbon. To permit the carbon to be removed, a hole 4 may be formed in the wall of the socket 2 so that a pointed instrument may be thrust beneath the carbon to force it from the socket. The peripheral wall of the socket 2 may be split or non-continuous to enable the carbon to be more readily set in position.

The upper carbon-holder preferably consists of a bolt 5 that passes through the upper carbon B', this upper carbon being formed with a central hole and with a countersunk portion to receive the nut 6 on the bolt of the carbon-holder. The head 7 of the bolt 5 passes through a cross-bar C of insulating material, suitable washers being preferably placed at opposite sides of the bar C where the bolt passes through it. The socket formed in the upper carbon B' to receive the nut 6 may be of polygonal shape to more securely retain the nut in position. The pair of carbons D and D' beneath the opposite end of the insulating bar C correspond in all respects to the carbons B and B', and the holders for these carbons are the same as the holders shown at the opposite side of the instrument.

Centrally through the insulating bar C is formed a hole through which passes a vertical rod 10, the lower end of which is embedded in the base A of the instrument. This rod 10 is provided at its lower portion with a sleeve or offset 11 against which bears the lower end of a coil spring 12, the upper end of this spring bearing against the underside of the bar C and serving to hold it normally in raised position. The upper end of the rod 10 is screw-threaded and is fitted with a nut 13 and jam-nut 14, so that the position of the bar C may be adjusted as desired to bring the carbons B, B' and D, D' in proper relation with respect to each other.

Electrical protective devices have heretofore been constructed in which two carbons are placed adjacent each other with insulating strips of mica or similar material between them, the purpose of such devices being to permit the short-circuiting of high potential currents through the carbons by the perforation of the mica strips when such

high potential currents trespass upon the line. Such prior device however is objectionable, because when the mica strips or like insulating material become punctured by the 5 passage therethrough of the high potential currents, there is danger of particles of carbon lodging in the opening formed through the insulating strip and serving to short-circuit through the carbons and through the 10 hole in the insulating strip, the low potential or normal current of the circuit.

One important feature of the present invention consists in forming the opposing faces of the carbons with elevations and depressions so that in case particles of carbon 15 should become detached by the passage through the carbons of high potential currents or otherwise, such particles of carbon will not serve to effect the short-circuiting of 20 low potential or normal currents of the circuit. Preferably the opposing faces of both the upper and lower carbons B, B' and D, D' are formed with grooves and ribs b, b' and d, d', the ribs or elevations of the upper carbons 25 being arranged opposite the corresponding ribs or elevations of the lower carbons. Hence it will be seen that any particles separating from the carbons (either because of the passage of high potential currents 30 therethrough or otherwise) will lodge within the depressions in the face or faces of the carbons and will not serve to short-circuit the low potential or normal current of the circuit.

35 The lower carbon-holders 2 rest upon and are preferably connected to a union strip 15 having an offset through which passes a binding-post 16 that is furnished with nuts 17 and 18 and from this binding-post 16 a 40 suitable wire 19 will lead to ground. The bolts 5 of the upper carbon-holders pass through the upper ends of the spring contact plates E and E', the lower ends of which 45 springs rest upon the upper face of the base A and through the lower ends of these contact plates E and E' pass the corresponding binding-posts 20 and 21, and the lower ends of the binding-posts 20 and 21 are preferably embedded in the insulating plate A. Each 50 of the binding-posts 20 and 21 is provided with the usual nuts 22 and 23 and to the binding-post 20 is connected the leading-in wire F of the circuit, while to the binding-post 21 is connected the leading-out wire F'. 55 The binding-posts 20 and 21 also pass respectively through the metal base strips g and g' whereon rest the standards G and G'. Preferably, although not essentially, each of the standards G and G' is formed from a 60 single strip of metal bent as shown more clearly in Fig. 5 of the drawing, and the open expanded bottom portion of each of these standards G and G' is connected to the base A by means of a bolt 25 that passes through 65 the corresponding strip g or g'. To the yoke-

shaped upper ends of the standards G and G' are pivotally connected, as by bolts 27, the rear ends of the fuse-casings H and H' that carry the fuse wires H² and H³ respectively, each of these casings being of like 70 construction.

In the preferred form of the invention the casings H and H', which are formed of suitable insulating material, are provided at their rear ends with metallic ferrules h having tubular screw-threaded shanks h' with which engage metal sockets J, through the rear extensions j of which sockets pass the pivot bolts 27. The front ends of each of the tubular casings H and H' are similarly 80 provided with metal ferrules h', the tubular screw-threaded portions h⁴ of which pass through a switch-handle bar K of suitable insulating material and are engaged by the threaded nuts h⁵. The fuse wires H² and H³ 85 at their front and rear ends are soldered or otherwise suitably connected respectively to the tubular shanks h' and h⁴ of the ferrules h and h'. Beneath the forward ends of the tubular casings H and H' are mounted the 90 metal posts or standards M and M', each of these posts being provided preferably with spring jaws m at its upper end to receive and 95 yieldingly engage the ferrule h³ of the corresponding casing H or H'. Each of the posts M and M' is suitably secured to the base A and these posts M and M' pass through metal strips 30 and 31 through which pass respectively the binding-posts 32 and 33. These 100 binding-posts 32 and 33 are furnished respectively with the usual clamping nuts 34 and from the binding-post 32 leads the out-wire N, while to the binding-post 33 is connected the in-wire N' of the circuit. The switch bar K is preferably furnished with a 105 handle k whereby it may be conveniently manipulated, although if desired this handle may be omitted.

From the foregoing description it will be seen that the low potential or normal current entering by the leading-in wire F will pass in manner well understood with those familiar with this class of devices, through the fuse-wire H² and connections to the out-wire N, to the instrument or instruments in 110 the circuit, and returning by the wire N', will pass through the fuse-wire H³ and connections to the leading-out wire F'. In case lightning or high potential current should invade the circuit, as by the leading-in wire F, 115 it will pass through the strip E, through carbons B and B' to base plate 15 and out by binding-post 16 and ground wire 19 to the ground. The working circuit and the instrument or instruments thereon will thus be 120 protected from injury.

Having described my invention what I claim is new and desire to secure by Letters Patent is:

1. A protective apparatus for electric cir- 130

cuits comprising a base-board, a cup-shaped carbon holder fixed to said base board, a post on said base-board, an arm adjustably carried on said post and a pair of carbon disks

5 one removably secured to said arm and the other removably held in the holder on said base, said carbon disks having oppositely disposed elevations on their adjacent faces, substantially as described.

10 2. A protective apparatus for electric circuits comprising a base-board, a pair of carbon holders fixed thereto, a post fixed to said base-board intermediate said carbon holders, a cross arm adjustably mounted on said post

15 and two pairs of carbons, two of which are removably secured to said arm and two of which are removably arranged within said carbon holders, substantially as described.

3. A protective apparatus for electrical circuits comprising two carbon-holders, one of which is provided with means whereby it may be electrically connected to the ground and the other of which is provided with means whereby it may be electrically connected to a 20 telephone or like circuit, one at least of the opposing faces of the carbons of said holders being formed with elevations and depressions, a spring for separating said carbon-holders and screw mechanism for adjusting said carbon-holders relatively to each other.

4. A protective apparatus for electrical circuits comprising two carbon-holders, one arranged above the other, a carbon block within each of said holders, a flexible spring 35 support for one of said carbon-holders connecting the same to the working circuit and electrical connection for uniting the other of said carbon-holders to ground, and means for adjusting said carbon-holders relatively to each other.

5. A protective apparatus for electrical

circuits comprising two pairs of carbon-holders, a base supporting the lower one of the carbon-holders of each pair, a connection uniting together the upper carbon-holders of 45 each pair a spring for separating said carbon-holders and screw mechanism for simultaneously adjusting the carbon-holders and their carbons relatively to each other.

6. A protective apparatus for electric circuits comprising a base-board, a carbon holder thereon comprising a continuous ring of spring metal having an annular, inwardly extending rib at its outer portion, a carbon disk removably fitting in said holder and having an annular recess adapted to be engaged by said rib and a second carbon disk adjustably supported adjacent said carbon holder.

7. A protective apparatus for electric circuits comprising a base, a pair of carbon holders fixed to said base, a post on said base intermediate said carbon holders, a spring supported cross arm adjustably mounted on said post, a pair of carbon disks removably mounted in said carbon holders and a second pair of carbon disks removably bolted to the ends of said cross arm.

8. A protective apparatus for electrical circuits comprising two carbon-holders, a base for supporting the lower one of said carbon-holders, a vertically adjustable spring-supported bar for carrying the upper one of said carbon-holders, said upper carbon-holder comprising a bolt suspended from said bar, and a carbon provided with a perforation to receive said bolt and being countersunk above the lower end of said perforation.
